(57) **CLAIM**

The ornamental design for a personal computing device display screen with an animated graphical user interface for trading platform, as shown and described.

DESCRIPTION

The file of this patent contains at least one drawing/photograph executed in color. Copies of this patent with color drawing(s)/photograph(s) will be provided by the Office upon request and payment of the necessary fee.

FIG. 1 is a front view of a first image of a personal computing device display screen with an animated graphical user interface for trading platform of the present invention; FIG. 2 is a front view of a second image thereof; and, FIG. 3 is a front view of a third image thereof.

The outer most broken line showing the display screen forms no part of the claimed design. The other broken line showing of the text and graphical elements forms no part of the claimed design.

The appearance of the animated images transition s between the images shown in FIGS. 1-3. The process or period in which one image transitions to another forms no part of the claimed design.
